UNITED STATES PATENT OFFICE.

JAMES M. FOLLETT AND LOUIS LEHNER, OF BAY CITY, MICHIGAN.

CLEAN-OUT ROUTER BIT.

Application filed December 11, 1925. Serial No. 74,729.

This invention relates to routing bits and the like and particularly to a cleanout routing bit for use in the wood working industry for routing and cleanout work.

One object of the invention is to design a cleanout routing bit of very simple and substantial construction which will be very economical to manufacture and extremely efficient in operation and which will eliminate the hand labor which heretofore has been necessary to clean out openings cut by hollow mortising chisels.

A further object is to design a routing bit having a friction collar for minimizing friction and wear between the bit shank and the edges of the work.

The above and other objects will appear as the specification progresses, reference being had to the accompanying drawing in which like reference numerals indicate like parts throughout the several views thereof.

In the drawing.

Fig. 1 is a side view of our improved cleanout routing bit.

Fig. 2 is a similar view, parts thereof being shown in section.

Fig. 3 is a top plan transverse sectional view taken on the line 3-3 of Fig. 2.

Fig. 4 is a side view of the friction collar.

Fig. 5 is a top plan view thereof.

Referring now particularly to the drawing in which we have shown the preferred embodiment of our invention, the numeral 5 indicates a conventional bit shank turned intermediate its length to form a shoulder 6, the extreme lower end 7 being further reduced and threaded, and is adapted to engage a threaded opening 8 provided in the turned tubular portion 9 of a cutting member 10.

This cutting member is of conventional design and the cutting edge 11 can be of any desired contour or shape to properly perform the work to be accomplished. A friction collar 12 is rotatably mounted on and embraces the shoulder 6 and tubular portion 9 of the cutting member proper, the fit being such that contact with the edge of the opening or groove to be cleaned, or shoulder of the work will allow the shank to freely revolve in the collar, thereby eliminating the friction of the driven bit shank against the edge or shoulder of the groove; this collar we prefer to make of brass to minimize wear.

The collar is lubricated by drilling an oil

passage 13 in the shank of the bit, leading to and opening onto the shoulder portion 6 of the shank.

When using hollow mortising chisels in wood members of various kinds, such as used in the construction of automobile bodies, furniture, etc., the bottom of the groove remains rough and uneven, and the small corners hang in the openings; these of course must be cleaned and smoothed, and heretofore this work has been done by hand labor using chisels, which is a slow and expensive operation, with our improved cleanout routing bit, this hand labor is entirely eliminated, and the work quickly and efficiently accomplished.

From the foregoing description it will be obvious that we have perfected a very simple, economical and efficient bit for routing and cleanout work.

What we claim is:—

1. A router bit comprising a shank, the lower end of which forms a cutter, a collar revolvably mounted on said shank directly adjacent the cutting end, said collar being of the same diameter as the cutting end.

2. A router bit comprising a shank, the lower end of which forms a cutter, a turned portion intermediate the length of said shank and a collar revolvably mounted on said turned portion, said collar being of the same external diameter as the shank.

3. A router bit comprising a shank having a turned shoulder intermediate its length and a reduced threaded lower end, a cutting member having a reduced interiorly threaded portion adapted to receive the threaded end of the shank, and a friction collar revolvably mounted on said shoulder, the external diameter of which is the same as the cutting member.

4. A router bit comprising a shank having a turned shoulder intermediate its length and a reduced threaded lower end, a cutting member having a reduced interiorly threaded tubular shoulder adapted to receive the threaded end of the shank, a friction collar mounted on said shoulders, and an oil passage in the shank opening onto said shoulder.

In testimony whereof we hereunto affix our signatures.

JAMES M. FOLLETT.
LOUIS LEHNER.
